UNITED STATES PATENT OFFICE.

JOSEPH H. BECKWITH, OF PINE BLUFF, ARKANSAS.

BRICK MOLD.

Application filed January 31, 1927. Serial No. 164,851.

This invention relates to molds and more particularly to a mold in which bricks, building blocks and the like may be formed. When clay bricks are molded or cement building blocks formed in a mold, it is some times difficult to remove the formed bricks or blocks from the mold. Therefore, one object of the invention is to provide a mold in which a number of blocks or bricks may be formed and the walls of the mold released and swung outwardly and downwardly out of engagement with the bricks or blocks so that they may be easily lifted off the bottom of the mold.

Another object of the invention is to provide the mold with side and end walls which may be interlocked with each other and to provide improved latches carried by the side walls and adapted to engage the end walls and securely but releasably retain the walls in an upright position.

Another object of the invention is to divide the mold into a number of compartments by partitions removably mounted between the side walls of the mold, certain of the partitions being formed with side extensions or cores which serve to provide mortar-receiving recesses in the rear faces of bricks or building blocks formed in the mold.

Another object of the invention is to so construct the mold that the bricks or blocks formed therein may be securely anchored when employed to form a wall and prevent them from accidentally working loose and dropping out of the wall.

The invention is illustrated in the accompanying drawings, wherein

Figure 1 is a top plan view of the mold;

Fig. 2 is a view showing the mold in side elevation;

Fig. 3 is a longitudinal sectional view through the mold;

Fig. 4 is a view showing the mold in end elevation;

Fig. 5 is an enlarged perspective view of one of the partitions forming part of the mold, and

Fig. 6 is a perspective view of a building block or brick formed in the mold.

The mold in which the improved building blocks or bricks are formed is provided with a bottom consisting of cross strips 1 nailed or otherwise secured upon longitudinally extending stringers 2. The side and end walls 3 and 4 are pivotally connected with the bottom by hinges 5 and 6 so that they may be swung from an upright position to a lowered

inoperative position where they will be out of the way and permit bricks and building blocks formed in the mold to be removed. Within the confines of the side and end walls 60 the cross strips forming the bottom are covered by a metal sheet 7 which provides a smooth bottom of the mold and prevents clay or cement from passing downwardly through the spaces between the cross strips. Cleats 65 8 are secured against the end strips 1 to engage the outer faces of the end walls when in an upright position and brace these walls in order to remove strain from the hinges and prevent the walls from being forced out of 70 a vertical position by pressure from within the mold. If desired, similar cleats may be provided to engage the side walls. By referring to Fig. 1, it will be seen that the side walls 3 have their end portions reduced in 75 thickness from their inner faces thereby providing tongue extensions 9 which fit into recesses 10 cut into the inner faces of the end walls. Therefore, close fitting joints will be 80 formed between the side and end walls and the walls will have interlocking engagement with each other. It should also be noted that the end walls have their upper faces cut to provide recesses 11 to receive the shank portions 12 of hooks 13 formed at the ends of 85 resilient latch strips 14. The latch strips 14 which extend longitudinally of the side walls 3 are secured against the outer faces thereof by screws or other suitable fasteners 15 and are of such length that their end portions project from the ends of the side walls for overlapping engagement with projecting end portions of the end walls. At their ends the latch strips are beveled to form cam surfaces 16 for engagement by the end walls so that, 90 when the side walls are swung upwardly to a raised or operative position, the end walls may be swung upwardly and by engagement with the cam surfaces lift the ends of the latch strips and move into proper engagement 95 with the ends of the side walls. When the end walls are raised, the tongue extensions 9 of the side walls fit into the seats 10 formed in the end walls and the hooks of the latch strips engage the end walls and serve to securely but releasably retain the walls elevated. When it is desired to release the walls so that they may be swung downwardly to permit removal of the bricks or building blocks formed in the mold, the end portions 100 of the latch strips are swung upwardly and the end walls can then be easily swung down- 105 110

wardly into a reclining position upon the bottom. The side walls will then be released and may also be swung downwardly. It will thus be seen that the walls are so formed that they may be securely held in an upright operative position but very easily and quickly released and swung downwardly.

In order to divide the mold into a plurality of compartments, there has been provided partitions 17 and 18 which extend transversely of the mold between the side walls and rest upon the sheet metal bottom. These partitions are preferably formed of wood and have their ends seated in grooves 19 formed in the inner faces of the side walls in order to properly space the partitions from each other and prevent them from moving out of proper spaced relation when in place. The partitions 18 are formed with flat uninterrupted side faces but the partitions 17 carry cores 20 which project transversely therefrom. These cores are formed of sheet metal and are provided with sloping side and end walls 21 and 22 which terminate in flanges 23 and 24 secured against the side faces of the partition by nails or other suitable fasteners driven through the flanges. By referring to Fig. 3, it will be seen that the partitions 17 and 18 are alternately disposed in the mold and when the compartments are filled with clay or cement each brick or block 25 formed will have one side face provided with a recess or pocket 26 adapted to receive mortar when set into a wall. It will be obvious that the shape of the core may be varied in order to form a recess of any desired length or configuration. By having the mold formed as shown, the walls may be easily swung upwardly to a vertical position and secured in interlocked relation to each other and the partitions then put in place and the compartments formed thereby filled with clay or cement. After the bricks have been formed or the cement sufficiently set to permit removal of building blocks the end walls are first released and swung downwardly and the side walls then lowered. After the walls are lowered it will be very easy to remove the bricks or blocks one at a time from the mold and then re-assemble the mold.

Having thus described the invention, I claim:

1. A brick mold comprising a bottom, side and end walls pivoted to said bottom, said end walls having their end portions overlapping the ends of said side walls and projecting transversely therefrom, the projecting end portions of the end walls being formed with recesses leading from their upper edge faces, and spring strips of greater length than the side walls secured intermediate their ends against the outer faces of said side walls and having their end portions projecting longitudinally therefrom and recessed from their under faces to provide shank portions fitting

into the recesses leading from the upper edge faces of the end walls and bills to engage the outer side faces of the end walls, the extreme end portions of said strips having their under faces beveled longitudinally to form cam surfaces.

2. A brick mold comprising a bottom, side and end walls pivoted to said bottom, said end walls having their end portions overlapping the ends of said side walls and their upper portions projecting transversely therefrom and formed with recesses leading from their upper edges, said side walls having their end portions reduced in thickness to form tongues and said end walls having their inner faces formed with grooves receiving the tongues of the side walls when the walls are upright, and spring strips secured against the outer faces of said side walls and having their end portions projecting longitudinally therefrom to overhang the end portions of the end walls and recessed from their under faces to provide hooks adapted to engage the outer faces of the end walls and having shank portions fitting into the recesses leading from the upper edge faces of the end walls when the hooks are engaged with the end walls.

3. A brick mold comprising a bottom, side and end walls carried by said bottom, and removable partitions resting upon said bottom and extending between the side walls with their ends engaging the same, alternate partitions being provided with core members projecting from opposite sides thereof whereby bricks formed in the mold will each have one side face formed with a recess.

4. A brick mold comprising a bottom, side and end walls carried by said bottom, and removable partitions resting upon said bottom and extending between the side walls with their ends engaging the same, alternate partitions being provided with flat unobstructed side faces, and core members secured against opposite side faces of partitions disposed between the portions having the flat side faces and projecting transversely of the partitions whereby bricks formed in the mold will each have a side face formed with a mortar receiving recess.

5. A brick mold comprising a bottom, side and end walls carried by said bottom, and removable partitions resting upon said bottom and extending between the side walls with their ends engaging the same, and core members carried by alternate partitions and projecting transversely from opposite side faces thereof to form mortar-receiving pockets in bricks formed in the mold, said core members being formed of sheet metal and each having sloping side and end walls terminating in attaching flanges secured against a side face of a partition.

In testimony whereof I affix my signature.
JOSEPH H. BECKWITH. [L.S.]
